A. M. Pierce.

ATTORNEY

UNITED STATES PATENT OFFICE.

FRANK PHILIP, OF STOCKPORT, NEW YORK.

SCRATCH-AWL.

SPECIFICATION forming part of Letters Patent No. 445,380, dated January 27, 1891.

Application filed February 24, 1890. Serial No. 341,448. (No model.)

To all whom it may concern:

Be it known that I, FRANK PHILIP, of Stockport, in the county of Columbia and State of New York, have invented new and useful Im-
5 provements in Scratch-Awls, of which the following is a specification.

My invention relates especially to devices employed for scratching or marking upon boards, timber, &c., and has for its object the provision of an awl which may be retained in the hand while working, the pointed portion being arranged to automatically return within the handle when pressure is removed from a manipulating thumb-piece, thus providing
10 an instrument very compact, cheap, and simple, while at the same time it is rendered harmless if dropped, and may be placed in the pocket.

To attain the desired end my invention
20 consists, essentially, in a tubular slotted handle, wherein plays a pointed rod provided with a manipulating thumb-piece which projects through the slot in the handle. A spring normally holds the rod drawn within
25 the handle, and said handle is provided with a finger-piece, all of which will be hereinafter first fully described, and then pointed out in the claims.

In the drawings, Figure 1 is a side elevation of my improved awl with the point projected, and Fig. 2 is a longitudinal sectional view with the point drawn in, showing the normal position of the various parts of the device. Fig. 3 is a rear elevation, and Fig. 4
35 a plan view, of the thumb-piece for manipulating the awl.

Like letters of reference, wherever they occur, indicate corresponding parts in all the figures.

40 A is a tubular handle, slotted at B. It is closed at C and drawn in at D.

E is a pointed rod encircled by a spring F, which finds a bearing at one end against the drawn-in portion of the tube and at the other
45 against a block G, secured to the inner end of rod E. This block G is provided with a manipulating thumb-piece H, which projects through the slot B. This thumb-piece is

depressed in at its center, preferably at an angle, in order to prevent the thumb from 50 slipping off while holding the awl in a projected position. This thumb-piece H projects through the slot in the side of the tube, and by pressing the thumb against it, when the tube is grasped in the hand, (where it is 55 easily held through the medium of the finger-piece I,) the awl will be forced out and held in the position shown in Fig. 1.

I is a finger-piece secured to handle A.

When in use, my improved scratch-awl may 60 be carried in the pocket with perfect safety or held in the hand, being retained there by means of the finger-piece, and when it is desired to scratch with the awl it is instantly caused to protrude by pressing the thumb 65 upon H. By my construction all danger of accident by dropping or falling upon the awl is obviated.

Having now fully described my invention, what I claim as new therein, and desire to secure by Letters Patent, is—

1. A scratch-awl in which is comprised a hollow slotted handle, a pointed rod playing in said handle and having a block at its inner end bearing a manipulating thumb-piece 75 which projects through the slot in the side of the handle, said thumb-piece being placed at an angle and having its center depressed, as set forth, and a spring which normally holds the awl drawn into the handle, substantially 80 as shown and described.

2. In a scratch-awl of the character herein specified, a tubular slotted handle closed at one end and having an opening at the other, a finger-piece secured to said handle, a pointed 85 rod within said handle provided with a manipulating thumb-piece projecting through the slot in the tube, and a coiled spring encircling the pointed rod, the whole combined and arranged to operate substantially as 90 shown and described.

FRANK PHILIP.
